[57] CLAIM

The ornamental design of an eyeglass frame, as shown and described.

DESCRIPTION

FIG. 1 is a frontal downward isometric view of an eyeglass frame according to my design;

FIG. 2 is a right elevational view thereof, the left elevational view being a mirror image of FIG. 2;

FIG. 3 is a front elevational view thereof;

FIG. 4 is a top planar view thereof;

FIG. 5 is a bottom planar view thereof; and,

FIG. 6 is a rear elevational view thereof.
